United States Patent Office

Des. 205,830
Patented Sept. 27, 1966

205,830

CRIB

Stephen J. Rudy, 107 Overlook Drive, Greenwich, Conn.

Filed May 3, 1965, Ser. No. 85,068

Term of patent 14 years

(Cl. D5—5)

FIG. 1 is a front perspective view of a crib, showing my new design; and

FIG. 2 is a rear end perspective view of the same.

The dominant features of the design reside in those portions shown in full lines on the drawing.

I claim:

The ornamental design for a crib, as shown and described.
